GLIDER

Edward E. Woller, Don Carlos Travis and Matthew F. Bayer, Kenosha, Wis., assignors to Simmons Company, New York, N. Y., a corporation of Delaware

Application July 5, 1934, Serial No. 733,748

9 Claims. (Cl. 5—126)

This invention relates to improvements in the construction of an article of furniture such as commonly called a "glider", and it has for its principal objects the provision of an improved construction which may be quickly and easily collapsed and set up to facilitate shipment and storage when not in use; the provision of such a structure which may be assembled or disassembled without the use of tools; the provision of a glider having swinging seat and back rest sections which are effectively held against endwise swaying by an exceptionally simple device which will not noticeably restrict the desired swinging movement; the provision of an improved and simplified seat and back rest arrangement which may be adjusted from normal angular relation to coplanar bed position; the provision of means for effectively locking the seat and back rest sections against swinging movement when in bed position; the provision of automatically actuated leg means for supporting the back rest section when in bed position; and in general, it is the object of this invention to provide an improved glider of the type referred to.

Other objects and advantages of the invention will be understood by reference to the following specification and accompanying drawings (4 sheets) in which there is illustrated a glider embodying a selected form of the invention.

In the drawings—

Fig. 1 is an end elevation;

Fig. 2 is a rear elevation of the end portion of the glider illustrated in Fig. 1;

Fig. 3 is a front elevation;

Fig. 4 is a longitudinal section on the line 4—4 of Fig. 1;

Fig. 5 is a front elevation of the main or supporting frame of the glider when in folded or collapsed condition for shipping or storage purposes;

Fig. 6 is an end elevation of the seat and back rest sections when in folded or collapsed condition for shipping or storage purposes;

Fig. 7 is a section on the line 7—7 of Figs. 3 and 4, the back rest section being shown turned down to form a bed;

Fig. 8 is a section on the line 8—8 of Fig. 7;

Fig. 9 is a plan of an end portion of the structure when in bed position; and

Fig. 10 is a perspective illustrating a detail of construction of the spring fabric of the seat and back rest sections.

Referring now to the drawings, the improved glider embodies a pair of end members 10 and 11 which are connected together by means of a

tie bar or member 12. The end members 10 and 11 are of substantially like construction and each embodies a base or foot member 13 of angle iron construction, upwardly extending angle iron posts 14 and 15 disposed in spaced relation, and a top member 16 which extends transversely of the posts 14 and 15 and is also formed of angle iron. The end member parts 13 to 16 inclusive are suitably secured together in relatively fixed relation by riveting or otherwise and braces such as indicated at 17 may be provided for strengthening the structure.

The end members 10 and 11 are each provided with a bracket 18 welded or riveted thereto in fixed relation and each bracket 18 is pivoted to the adjacent end of the tie bar 12 by means of a rivet or the like indicated at 19. It will be seen that the end members 10 and 11 are thus pivotally or foldably connected to the tie member 12 so that they may be folded from normal or operative upright position, as shown in Figs. 1, 2, 3 and 4, to the collapsed position illustrated in Fig. 5.

For supporting the end members in their upright position, there are provided two, more or less Y-shaped, braces designated 20, 20. Each Y-brace 20 includes forked arms 21 and 22 which have their free ends pivoted respectively to the upright posts 14 and 15 of the respective end members. The end of the other arm 23 of the Y-brace is provided with a disengageable pin and slot connection with the tie bar 12. The pin and slot connection referred to includes, in this instance, a pin 24 secured to the tie bar 12 and an inverted keyhole opening 25 in the end of the said arm 23. The pin 24 is provided with a head of larger diameter than the shank of the pin, the head of the pin being of such size that it will fit through the enlarged part of the keyhole opening 25 but not through the smaller portion. Thus the braces 20 may be engaged with the tie bar 12 by a slight lateral movement of the brace relative to the tie bar so as to cause the head of the pin 24 to extend through the enlarged part of the opening 25 and a subsequent swinging movement of the brace about its pivotal connections with the posts 14 and 15 of the end member. This engagement of the braces and tie bar is of course accomplished by reverse movement of the parts. It may be observed that the various parts are sufficiently flexible to permit the necessary amount of lateral movement to engage or disengage the braces from the pins 24.

The seat and back rest sections 26 and 27 each include iron border frames which are pivoted

5

35

40

45

50

55

or hinged together through the agency of brackets 28 and 29 respectively secured to the seat and back rest sections and pivoted together as indicated at 30. Such hinged connections are provided at each end of the seat and back rest sections.

Front and rear legs 31 and 32 respectively depend from the border frame of the seat section in fixed relation thereto and these legs are connected by means of transversely extending angle iron members such as indicated at 32. Corner braces such as indicated at 33 may be provided for further reinforcing the structure.

Swingably mounting the seat and back rest sections in the main supporting frame, there are provided front and rear hangers 34 and 35 which depend from the front and rear ends respectively of the top cross members 16 of the respective end members. The hangers 34 and 35 may be connected to the top member 16 in any suitable manner, for example, by means of links such as indicated at 36.

The front hangers 34 are connected to the front portion of the seat section 26 through the agency of bars 37, 37 which have their outer ends anchored to the lower ends of the hangers 34 through the agency of links such as indicated at 38, 38. Intermediate their lengths, the bars 37 are provided with transversely extending stop pins 39 and at their inner ends, the bars 37 have inverted keyhole openings designated 40.

The inner end portions of the bars 37, 37 are adapted to be positioned in slots such as indicated at 41 (Fig. 6) in the lower ends of the front legs 31 of the seat section, the keyhole openings 40 of the said bars being adapted to engage headed pins designated 42 carried by corner braces 43 extending between the front legs 31 and the border frame of the seat section. The pin and slot connections 40, 42 are similar to the pin and slot connections 24, 25 previously described and are engageable and disengageable in the same manner. The stop pins 39 serve to facilitate engagement of the pin and slot connections 40, 42 by properly positioning the bar 37 with respect to the leg 31 and corner brace 43 and the said stop pin also relieves the headed pin 42 of some of the strain incident to the supporting of the seat section.

50 The rear hangers 35, 35 are each connected to a rear leg 32 by means of a similar arrangement, which is best shown in Figs. 1 and 2. These connections each include a bar 44 which fits slidably through an opening 45 in one of the depending rear legs 32 of the seat section. The outer end of the bar 44 is connected through the agency of a link 46 to the lower end of the hanger 35 and the inner end of the bar is detachably connected by another pin and keyhole opening connection 55 with the lower end of a corner brace member 47 which extends between the upper end of the rear leg 32 and a longitudinally extending tie bar 48 which connects the rear legs 32 at the opposite ends of the seat at a distance below the surface 60 of the seat. For purposes which will presently appear, the connection between the front end of the bar 44 and the link 46 may be readily disengageable by leaving the link 46 open sufficiently to disengage the link from the bar.

70 The back rest section 27 is adapted to be unfolded from collapsed position illustrated in Fig. 6 to operative position in angular relation to the seat section, substantially as illustrated in Fig. 1. The back rest section is supported in the said

operative or upright position and also in further unfolded bed position, as illustrated in Fig. 7, through the agency of a leg structure which embodies legs such as indicated at 49 respectively connected to the ends of the back rest section by means of a pivot connection such as indicated at 50. Such legs are connected for rigidity and for simultaneous movement through the agency of a longitudinally extending angle iron bar 51 which is offset rearwardly intermediate its ends 5 so as to avoid interference with the yielding bed spring fabric carried by the back rest frame, as will presently be described. The lower end of each leg 49 is connected by means of a strut 52 to a normally fixed pivot designated 53. The 10 pivot 53 comprises a headed pin carried by the lower end of the link 52, the said pin being adapted to fit in a slot 54 provided in a bracket 55 which is secured to and extends rearwardly from the adjacent rear legs 32 of the seat section. A 20 hook element 56 pivoted at one end to the bracket 55, is provided for also engaging the headed pin to lock the same in the slot 54, as will be readily understood by inspection of Fig. 1. The upper end of the strut 52 is pivoted to the lower end 25 portion of the leg 49, as indicated at 57.

It will be seen that when the back rest section 27 is in the position illustrated in Fig. 1, the strut 52 and leg 49 will support the back rest section because the leg rests against the inwardly projecting front flange of the back rest frame and the pivot 57 is in an over-the-center position with respect to the pivots 50 and 53. To effect unfolding of the back rest section to bed position, it is necessary to swing the back rest section slightly 30 forwardly on its pivot connection 30 with the seat section so as to permit the legs 49 and struts 52 to be swung rearwardly about their respective pivots 50 and 53. As soon as the over-the-center 35 relationship illustrated in Fig. 1 is overcome and reversed, the weight of the back rest section will 40 of course tend to effect unfolding to bed position illustrated in Fig. 7.

For the purpose of elevating the rearward portion of the seat section and the adjacent portion of the back rest section from the lowered seat position illustrated in Fig. 1, to the elevated position illustrated in Fig. 7, which is substantially in a horizontal plane with the normal elevation of the front portion of the seat section, the following arrangement is provided. A link or strut element 58 is pivoted at its upper end as indicated at 59 to the hinged bracket 60 of the back rest section. As indicated, the pivot 59 is spaced rearwardly or downwardly from the hinged pivot 30. The lower end of the strut 58 is pivoted as indicated at 61 to the arm 44. When the back rest section is unfolded to bed position, it will be seen that the pivot 59 approaches a position of alignment with the pivots 30 and 61. In so doing, the distance between the pivots 30 and 61 is of course necessarily increased to accommodate the combined distances between the pivots 61 and 59 and between the pivots 59 and 30. Thus 55 the rearward portion of the seat section 26 and adjacent portion of the back rest section is elevated to bed position illustrated in Fig. 7.

When the back rest and seat sections are in bed position illustrated in Fig. 7, the inner side 70 portions thereof adjacent the pivot connection 30 therebetween, are supported in their horizontal bed position at a greater height relative to the lower end of the hanger 35 than when the parts are in glider position, by means of the 75

strut 58, the bar 44 being swung downwardly at its outer end on its pivot connection with the brace 47. The brace 47 and the strut 58 cooperate in transmitting the load from the adjacent portions of the seat and back rest sections to the bar 44 from which the load is transmitted to the hanger 35 and to the end frame. The slot 45 in the leg 32, through which slot the bar 44 passes, permits said pivotal movement of the bar while preventing sidewise displacement thereof.

When the seat and back rests are in folded position as shown in Fig. 1, the weight of the rear portion of the seat section is transmitted directly to the bar 44 by engagement between the edge of the leg 32 at the upper end of the slot 45 and said bar, the brace 47 then serving to prevent upward rocking of the outer end of the bar 44 about said point of engagement as a fulcrum.

The pivots 59 and 61 are made a very loose fit, so that when the glider structure is to be assembled or disassembled, the link 46 may be disengaged from the outer end of the arm 44, the inner end of the arm 44 disengaged from the brace 47 and the arm then drawn outwardly through the slot 45. In so withdrawing the arm 44, the strut 58 is of course caused to swing laterally outwardly about its upper pivot 59, substantially as indicated in broken lines in Fig. 2. By thus withdrawing the arm 44 from the leg slot 45, it is possible to fold the arm 44 into substantial alignment with the strut 58, and to fold the arm 44 and strut 58 about the pivot 59 to an overlapping position on the back of the back rest section when in collapsed condition, as illustrated in Fig. 6. This arrangement is desirable for shipping and storing purposes, and it will be seen that it eliminates an element which projects from the ends of the seat section and which would be objectionable in shipment and storage.

The spring fabric of the seat and back rest sections is shown in this instance as being of wire or link type. It is resiliently supported within the frames of the respective sections by means of hanger springs 62.

The back rest portion of the spring fabric is connected to the seat portion thereof by means of special links 63 each of which has arms 64 and 65 extending through the loops 66 in the adjacent edges of the back rest and seat section spring fabric portions. The free ends of the arms 64 and 65 are hooked as indicated at 67 to the adjacent loops 66 so as to prevent displacement of the links 63. The arms 64 and 65 of the links are freely slideable through the loops 66 in the edge of the other spring fabric portion.

The described connection between the spring fabrics of the two sections is such that the back rest and seat sections may readily be folded as previously explained, the spring fabric portions being readily foldable with the respective sections. The connections between the respective portions of the spring fabric serve to prevent displacement of cushions or bedding between the respective fabric sections and they serve to unite the same into a continuous, in effect, a single bed spring fabric extending across the entire width of the combined seat and back rest sections when in bed position.

To prevent the seat and back rest sections from swaying in an endwise direction, there is provided a stabilizing rod or bar designated 68.

This member may be in the form of an angle iron which is turned to the inverted V-shaped position best shown in Fig. 1. The opposite ends of the member 68 are provided with apertures and one end of the member is engaged with a pin 69 carried by a bracket 70 which extends upwardly from the tie bar 12. The other end of the stabilizer 68 is engaged with a pin 71 which extends upwardly from the angle iron cross member 72 which extends between the front and rear legs 31 and 32 of the seat section. A reinforcing angle iron member 72 is provided on both ends of the seat section and a bracket element 73 secured to the member 72 is provided with oppositely inclined upper edges 74 and 75 and an intermediate notch 76. The inclined edges 74 and 75 and the notch 76 are adapted to cooperate with a stop member 77 carried by and projecting inwardly from the upright post 15 on each of the end frames 10 and 11. When the glider is adjusted to bed position, the inclined edges 74 and 75 have the effect of engaging the bottom of the stop member 77 to guide the seat section to predetermined position transversely of the main supporting frame and in that position, the notches 76 receive the lower portion of the stop member 77 to lock the seat section against further swinging movement.

Changes in the described structure may be made without departing from the spirit of the invention, the scope of which should be determined by reference to the following claims, the same being construed as broadly as possible consistent with the state of the art.

We claim:

1. In a glider of the class described, the combination of hingedly connected seat and back rest sections which are adjustable from angularly related glider position to substantially coplanar bed position, an arm extending endwise from said seat section and adapted to engage means for supporting said seat and back rest sections, said arm being connected to the seat section so as to be fixed transversely of the section and vertically adjustable relative thereto, and means for effecting upward adjustment of the hinged side of the seat section to bed position as an incident to the adjustment of the back rest section to said bed position, said means comprising a strut pivoted at its ends respectively to said vertically adjustable arm and to said back rest section in spaced relation to the axis of the hinged connection between the seat and back rest sections.

2. In a glider of the class described, the combination of hingedly connected seat and back rest sections which are adjustable from angularly related glider position to substantially coplanar bed position, a main frame for supporting said sections, a hanger depending from said supporting frame for swingably supporting said seat and back rest sections, an arm extending between said seat section and hanger for connecting the same, said arm being connected to the seat section so as to be fixed transversely of the section but vertically adjustable relative thereto, means for effecting upward adjustment of the hinged side of the seat section to bed position as an incident to the adjustment of the back rest section to said bed position, said means comprising a strut pivoted at its ends respectively to said vertically adjustable arm and to said back rest section in spaced relation to the axis of the hinged connection between the seat and back rest sections, and cooperating means car-

35

50

55

60

- ried by said seat section and supporting frame for locking the seat section against swinging movement when said section is elevated to said bed position.
5. 3. In a glider of the class described, the combination of hingedly connected seat and back rest sections which are adjustable from angularly related glider position to substantially coplanar bed position, a main frame for supporting said sections, a hanger depending from said supporting frame for swingably supporting said seat and back rest sections, an arm extending between said seat section and hanger for connecting the same, said arm being connected to the seat section so as to be fixed transversely of the section but vertically adjustable relative thereto, means for effecting upward adjustment of the hinged side of the seat section to bed position as an incident to the adjustment of the back rest section to said bed position, said means comprising a strut pivoted at its ends respectively to said vertically adjustable arm and to said back rest section in spaced relation to the axis of the hinged connections between the seat and back rest sections, and cooperating means carried by said seat section and supporting frame for locking the seat section against swinging movement when said section is elevated to said bed position, said cooperating means including a part carried by the main frame and another part carried by said seat section, one of said parts having cam surfaces for acting on the other part to effect transverse movement of the seat section to predetermined position transversely of the main frame preliminarily to said locking action.
4. In a glider of the class described, the combination of hingedly connected seat and back rest sections which are adjustable from an angularly related glider position to a substantially co-planar bed position, means for supporting said seat and back rest portions for swingable movement, means for effecting upward movement of at least the hinged end of said seat section from glider position to bed position as an incident to the lowering of said back rest section to bed position, and means carried by said seat section which is moved into interlocking engagement with cooperating means forming a part of said supporting means by the upward movement of said seat section consequent to the lowering of said back rest section, said interlocking means serving to positively lock said seat and back rest sections from swingable movement when said glider is in bed position.
5. In a glider of the class described, the combination of hingedly connected seat and back rest sections which are adjustable from an angularly related glider position to a substantially co-planar bed position, means for supporting said seat and back rest sections for swingable movement, means for effecting upward movement of at least the hinged end of said seat section from glider position to bed position as an incident to the lowering of the back rest section to bed position, and means carried by said seat section which is moved into interlocking engagement with cooperating means forming a part of the support for the glider by the upward movement of said seat section consequent to the lowering of said back rest section, said interlocking means serving to positively lock said glider from swingable movement with respect to the supporting frame therefor when said glider is in bed position and including a plate member having a generally V-shaped notch formed therein and a suitable cooperating member for engaging said notch.
6. In a glider of the class described, a seat section and a back rest section hingedly connected together so as to permit said back rest section to be lowered from an upright glider position to a horizontal bed position, means including a stationary structure for supporting said seat and said back rest sections for swingable movement when those sections are in the glider position, and means actuatable by the lowering of said back rest section to bed position to interlock said supporting means and said hingedly connected seat and back rest sections.
7. In a glider of the class described, a seat section and a back rest section hingedly connected together so as to permit said back rest section to be lowered from an upright glider position to a horizontal bed position, means actuatable when said back rest section is lowered to glider position to raise at least a portion of said seat section, means for supporting said seat section and said back rest section for swingable movement, and means carried by said seat section which is movable into interlocking engagement with cooperating means forming a part of said supporting means by the upward movement of said seat section incident to the lowering of said back rest section.
8. In a glider of the class described, a movable structure including a seat section and a back rest section hingedly connected together so as to permit said back rest section to be lowered from an upright glider position to a horizontal bed position, a stationary structure, and means for supporting said movable structure upon said stationary structure in such manner that said movable structure is swingably movable relative thereto when said seat and back rest sections are in the glider position, said supporting means including a lever pivotally supported at one of its ends upon said movable structure, the other end of said lever being mechanically connected to said stationary structure, and means actuatable by the movement of said back rest section when that section is lowered from the glider to the bed position to move said lever about its pivot and thereby vary the relative positions of said movable structure and said stationary structure.
9. In a glider of the class described, a movable structure including a seat section and a back rest section hingedly connected together so as to permit said back rest section to be lowered from an upright glider position to a horizontal bed position, a stationary structure, and means for supporting said movable structure upon said stationary structure in such manner that said movable structure is swingably movable relative thereto, said means including a lever pivotally supported at one of its ends upon said stationary structure and slidably engaging a slot formed in said stationary structure intermediate its ends, the other end of said lever being mechanically connected to said stationary structure, and means including a toggle linkage actuatable by the movement of said back rest section when that section is lowered from the glider to the bed position to move said lever about its pivot point and thereby raise one end of said seat section.

EDWARD E. WOLLER.
DON CARLOS TRAVIS.
MATTHEW F. BAYER.
